UNITED STATES PATENT OFFICE.

WILLIAM VAN HORN, OF PIQUA, OHIO.

WEATHER-STRIP.

No. 800,342.

Specification of Letters Patent.

Patented Sept. 26, 1905.

Application filed November 29, 1904. Serial No. 234,765.

To all whom it may concern:

Be it known that I, WILLIAM VAN HORN, a citizen of the United States, residing at Piqua, in the county of Miami and State of Ohio, have 5 invented certain new and useful Improvements in Weather-Strips, of which the following is a specification.

This invention has relation to improvements in weather-strips; and the main feature of the 10 invention resides in the provision of means of this type having desirable non-binding qualities and at the same time comprised of a structure having a certain amount of cushion action or effect in preventing rattling of the window 15 or like part to which the invention may be applied.

Further, the invention resides in the provision of special means whereby the weather-strip may be quickly and easily applied to the 20 window structure, if it be in this capacity, the above constituting an essential and important feature of the invention.

For a full description of the invention and the merits thereof and also to acquire a knowledge 25 of the details of construction of the means for effecting the result reference is to be had to the following description and accompanying drawings.

While the invention may be adapted to different 30 forms and conditions by changes in the structure and minor details without departing from the spirit or essential features thereof, still some of the preferred embodiments are shown in the accompanying drawings, in 35 which—

Figure 1 is a broken sectional view showing the preferred embodiment of the invention. Fig. 2 is a broken perspective view bringing out more clearly the construction of the parts 40 of the strip. Fig. 3 is a broken sectional view illustrating a modified application of the invention.

Corresponding and like parts are referred to in the following description and indicated 45 in all the views of the drawings by the same reference characters.

The invention is shown as when used in connection with windows, and in the drawings the numeral 1 designates the window-jamb, 2 the 50 parting-strip, and 3 the usual stop-strips holding the window-sash 4 of the window in place. In its preferred contemplation the weather-strip comprises a body folded upon itself to form spaced sides 5 and 5^a, and extending 55 from the sides 5 of the strip at an angle thereto is a flange 6. The flange 6 is folded longi-

tudinally of the edge portion to form a fold or second flange 6^a, the purpose of which will be seen more clearly hereinafter. The window-sash 4 is provided in its side with a longitudinal recess or slot 7, the latter being designed to receive the body of the weather-strip, so as to effectively exclude dust or foreign matter.

Peculiar means are utilized for holding or 65 securing the weather-strip in place, and for this purpose a base strip or plate 8 is utilized, said part being secured to the jamb 1 of the window in the runway of the sash 4 adjacent. Each strip or plate 8 is secured by means of a 70 suitable number of fastenings 9, as shown in Fig. 1, and one edge portion of the strip 8 is preferably received between the adjacent stop 3 and the jamb 1. The other edge portion of the strip 8 is received in the longitudinal fold 75 of flange portion 6^a of the weather-strip when the base-strip 8 is in place. The same serves to hold the weather-strip in proper position, with the body thereof in the slot or recess 7 of the adjacent sash 4. In other words, the strip 8 80 clamps the weather-strip in place, and the fastenings 9 of said strip 8 are so located that the weather-strip overlaps or covers said fastenings in such a manner that the sash 4 cannot come into contact with the fastenings. The 85 sides 5 and 5^a of the weather-strip being spaced form a cushioning means or resilient bearing, which readily takes up any lateral play or motion of the window in a manner which will be very clear.

From the foregoing it will be noted that the securing means for the weather-strip is such that the latter may be readily detached when it is not desired to use the same, since by a sliding perpendicular movement the weather-strip 95 can be readily and quickly disengaged from the base-strip 8, with which it is interlocked by means of the part 6^a. The base-strip 8 may be left in the runway of the sash 4 when the weather-strip has been removed and will not 100 interfere with the free movement of the sash whatever.

Fig. 3 of the drawings illustrates a modification of the invention, and in this structure instead of providing the interlocking member 105 upon the weather-strip the base-strip 8 is formed with a longitudinal fold or flange 8^a at one edge thereof, and this flange receives a flange 10, projecting from one of the sides of the body of the weather-strip. The weather-strip in Fig. 3 also covers the fastenings of the base-strip 8. A second flange 11 extends

from the side of the body of the weather-strip opposite that from which the flange 10 extends, and said flange 11 may contact with the fold or flange 8^a of the base-strip in limiting the 5 movement of the side 5^a of the weather-strip.

Having thus described the invention, what is claimed as new is—

1. In combination, the window-frame 1, the sash 4 provided with the recess 7 in a side 10 thereof, the base-strip 8 in the runway of the frame 1, the weather-strip composed of a body folded upon itself to form spaced sides extending at an angle to the base-strip 8 and received in the recess 7 of the sash 4, the flange 15 projected from the body aforesaid, and interlocking means between said flange and the base-strip 8.

2. In combination with a window-frame and sash mounted therein, a weather-strip having 20 the body thereof folded to form spaced sides, a flange projecting outwardly from one of the sides of the strip, a base-strip applied to the

window-frame, and interlocking means between the flange of the weather-strip and the base-strip aforesaid.

25

3. In combination with a window-frame and sash mounted therein and having a longitudinal slot or recess in a side thereof, a base-strip secured to the window-frame in the runway of the sash aforesaid, a weather-strip comprising a body folded upon itself to form spaced sides received in the recess of the slot of the sash, a flange projecting from one of the sides of the body of the weather-strip and bent upon itself to form a fold interlocking 30 with the base-strip aforesaid, and fastenings for the base-strip covered and overlapped by the weather-strip aforesaid.

30

In testimony whereof I affix my signature in presence of two witnesses.

WILLIAM VAN HORN. [L. S.]
